ATOMIZER

Barnett Baron, Bronx, N. Y.

Application January 7, 1947; Serial No. 720,605

3 Claims. (Cl. 299—89)

1

This invention relates to atomizers for dispensing cleaning fluids, insecticides and the like.

It is an object of the present invention to provide an atomizer which will be easily handled and operated and may be operated by a single hand if desired and without requiring the use of two hands to effect its operation such as where one hand must necessarily be extended about the container while the other hand is operating the air bulb.

It is another object of the present invention to provide in an atomizer a catch wall on the top of the container so as to prevent the drippings from the outlet of the atomizer from passing downwardly over the side of the can so as to be engaged by the hand of the user of the atomizer or to be deposited upon a support on which the atomizer may be rested.

It is another object of the present invention to provide an atomizer wherein an air pressure can be built up above the liquid within the container so as to add to the effectiveness of the atomizing action and to assist in the expulsion of the liquid and wherein the arrangement is of simple construction and formed in a single unit separable from the container along with the bulb and operating parts.

It is another object of the present invention to provide an adjustment whereby the amount of spray can be controlled and the adjustment set for the different liquids being dispensed.

It is another object of the present invention to provide an atomizer which is of simple construction, cheap to manufacture and efficient in operation.

For other objects and for a better understanding of the invention, reference may be had to the following detailed description taken in connection with the accompanying drawing, in which:

Fig. 1 is a top plan view of my atomizer showing the support for the bulb and the protecting portion on the top of the container for collecting nonatomized liquid.

Fig. 2 is a side elevational view of my atomizer as shown in Fig. 1 and with a portion broken away to show the connection of the cap with the top of the container and the space in which non-atomized liquid is collected at the top of the container.

Fig. 3 is an enlarged fragmentary and cross-sectional view taken on line 3—3 of Fig. 1 and looking in the direction of the arrows thereof and through the cap or head on which the bulb is connected.

Fig. 4 is an enlarged and transverse cross-sec-

2

tional view taken through the receiving pipe carried upon the head and which extends downwardly into the bottom of the container.

Figs. 5 and 6 are longitudinal cross-sectional views taken of the lower end of the receiving pipe with the adjusting screw for controlling the flow of liquid into the pipe being in two different positions, the position in Fig. 5 being that in which the end of the pipe is closed by the adjusting screw as at times of shipping while in Fig. 6 shows the screw slightly removed from the lower end of the pipe.

Referring now to the figures, 10 represents a container having a flat bottom adapted to rest upon a support and having a neck portion 12 at its top on to which a cap 13 is screwed. Surrounding the neck portion 12 is a wall portion 11 concentrically arranged so as to collect any of the liquid which may have drained from a head portion 14 on the cap 13. Such liquid will be collected within the wall portion 11 and thus prevented from draining down the side of the container 10 so as to get upon the hands of the person handling the container or upon the support on which the bottom of the container is rested. The cap 13 has a gasket 15 therewith so as to make an air tight connection with the neck portion 12. Extending from the side of the head portion 14 is an air inlet nipple 16 to which a rubber tube 17 is connected. The outer end of the rubber tube 17 has an air bulb 18 connected to it whereby the head portion 14 can be supplied with air and air forced through a small passage 19 in the head portion 14. Such air will also be directed downwardly through a passage 20 in the head portion to the top of the liquid in the container so as to provide a pressure thereupon to assist the atomizing action. Also there is a passageway 21 which extends upwardly through the head portion 14. To the head portion and in communication with the passageway 21 there is connected the threaded end 22 of a receiving pipe 23 which extends downwardly to the bottom of the container.

Upwardly through the pipe 23 the liquid is drawn and into the passageway 21 from which it leaves by injector action of the air leaving the left side of the passage 19. Thus air and atomized liquid will be dispensed through a hole 19 in the side of the head portion 14.

In the bottom end of the pipe 23 there is connected a screw portion 24 of a screw head 26 by screwing action on an internally threaded portion 25 of the pipe 23. With the screw head 26 in the position shown in Fig. 5 the surfaces of

the screw head will engage with a surface 27 on the bottom end of the pipe and tend to close the same so as to prevent fluid from entering the pipe. This has an advantage as when it is desired to ship the container with the liquid in it.

When the atomizer is to be set up for operation the screw thread 26 is turned downwardly to a position shown in Fig. 6. Liquid will enter between the threads and move upwardly into the pipe 23. The adjusting screw 26 has an extension 28 which extends upwardly into the top end of the pipe 23. This extension 28 is of less diameter than the interior diameter of the pipe so as to permit the free passage of liquids upwardly through the pipe. The extension 28 is of square section as shown more clearly in Fig. 4. It will be apparent that while it is not necessary that the hole which extends through the pipe be so large in order to get a supply of liquid to the top of the same and into the head portion, that there has been provided a structure whereby the small hole for the passage of liquid can be provided without the necessity of a delicate drilling or machining operation. It would be difficult to have such a hole of such small size in a pipe which extends down to the bottom of the container and if such an arrangement were provided it would be difficult to effect a cleaning operation of the same. With the present structure the pipe 23 can be removed from the head portion 14 and the extension 28 taken out thereof and the pipe readily cleaned. At the same time the passage of liquid through the same is limited and there is little opportunity for a great amount of air to be within the liquid which is raised to the head portion 14 as would be the case if a larger opening were extended upwardly from the bottom of the container.

It will be noted that the threaded portion 24 has a flat portion 24' which will permit a larger flow of liquid into the end of the pipe 23 should the screw portion 24 be withdrawn to a greater distance from the bottom end of the pipe than as shown in Fig. 6. Accordingly there has been provided an adjusting screw for controlling the amount of liquid to enter and be raised in the pipe.

In order that the atomizer may be totally closed for the purpose of shipment with liquid therein, there is provided at the bottom end of the passage 20 screw threads 34 into which a screw can be inserted along with a sealing washer.

Fixed to the cap 13 is a laterally and downwardly inclined portion 29 which serves as a support for the bulb 18 and which can be grasped by the same hand that grasps the bulb so that the container with the liquid can be raised by the same hand that grasps the bulb. Accordingly one hand can be used for dispensing the atomized fluid. The bulb 18 is simply pressed against the laterally extending portion or shelf 29. This portion 29 is curved on its top face to nicely receive the bulb 18 and to prevent the bulb from being laterally offset from the same.

The bulb 18 will have two valves therein so that it acts as a pump. When this bulb is taken with the laterally extending portion or shelf 29 there is provided a handle for the atomizer. In other words the pump is formed in the handle. Instead of a bulb type of pump, a piston or plunger type or an electric pump can be used, and these later pumps can also be incorporated in the handle.

While various changes may be made in the detailed construction, it shall be understood that such changes shall be within the spirit and scope

of the present invention as defined by the appended claims.

I claim:

1. An atomizer comprising a container having an opening portion thereon, a closure element adapted to be removably connected to the opening portion of the container, said closure element having a head portion with an air passage extending transversely therethrough and two vertically extending passages extending from the lower end of the head portion and communicating with the transversely extending air passage, means for forcing air through the transverse air passage, one of said vertically extending air passages serving to supply air pressure to the top of liquid within the container and the other of said vertically extending passages serving to communicate liquid to the transverse passage to atomize and dispense the same, a separable pipe connected to the head portion in communication with the vertically extending passage which receives the liquid, an adjustable and removable liquid control element engageable with the bottom of the pipe, and means extending from the control element upwardly into the top of the pipe and into the head portion of the closure element to provide capillary space within the pipe and head portion for the flow of liquid, whereby the amount of liquid entering the pipe can be controlled and whereby the liquid passage of the atomizer can be cleaned by the removal of the adjustable control element from the pipe and the pipe from the closure element.

2. An atomizer comprising a container having an opening portion, a closure element adapted to be removably connected to the opening portion of the container, said closure element having a head portion with a horizontally extending air passage therein, means for supplying air under pressure to the air passage, said head portion further having two vertically extending passages communicating with the horizontally extending air passage, one of said vertically extending passages serving to supply air under pressure to the top of the liquid contained within the container, a pipe connected to the head portion in communication with the other vertically extending passage and extending downwardly to the bottom of the container, an adjustable and removable liquid control element adjustably connected to the bottom of the pipe and extending upwardly thereinto to limit the flow of liquid passing through the bottom end of the pipe, an extension on the control element having a flat face and extending upwardly through the pipe into the upper end thereof and into the head portion of the closure element, said flat face of the extension providing for a capillary passage throughout the length of the pipe between the extension and the interior wall face of the pipe, the lower end of the pipe having a threaded interior and the adjustable control element being threaded to engage therewith whereby the amount of liquid entering the pipe can be controlled and upon the control element and its extension being removed, the pipe can be readily cleaned.

3. An atomizer as defined in claim 2, and said control element having a tapered face thereon, the lower end of the pipe having a countersunk face adapted to be engaged by the tapered face of the control element to permit the engagement therewith of the tapered face whereby to shut off the flow of liquid upwardly through the pipe

5

at times when the container is being shipped with the liquid.
